WIDE BAND PHASE SHIFTER

Kenneth George Hodgson, London W. C. 2, England, assignor to International Standard Electric Corporation, New York, N. Y.

Application February 27, 1942, Serial No. 432,688
In Great Britain January 31, 1941

13 Claims. (Cl. 178—44)

It is frequently necessary in the communication art that currents or voltages in two or more branches of a circuit shall, over a certain frequency range, differ in phase by a constant angle—most usually 90 degrees—and have the same amplitude or a constant amplitude ratio. It is the purpose of this invention to provide improved means for obtaining a close approximation to this condition over a wide frequency range.

In order to achieve this object a network having substantially constant attenuation over the required frequency range is placed in each branch of the circuit, the networks being so designed that their insertion phase angles in the required frequency range follow approximately the following laws:

$$\begin{aligned} \theta_1 &= A_1 + A_0 \log f \\ \theta_2 &= A_2 + A_0 \log f \\ \theta_3 &= A_3 + A_0 \log f \\ &\text{etc.} \end{aligned} \quad (1)$$

By suitable choice of the constants A_1 , A_2 etc. the phase difference between any two branches may be adjusted to any value and will remain substantially constant over the required frequency range.

It has been found that certain constant resistance, all-pass networks can be designed to approximate very closely to the desired characteristics.

Figures 1, 2 and 3 show three types of all-pass lattice networks. In each case the impedance arms are inverse i. e.

$$\frac{L_{11}}{C_{11}} = \frac{L_{22}}{C_{22}} = \frac{L_{12}}{C_{12}} = R^2$$

where R is the characteristic impedance.

In the network of Figure 1 if:

$$L_{11} = \frac{K_0 R}{\pi f r}$$

and

$$x = \frac{f}{f r}$$

then

$$\theta = 2 \tan^{-1} K_0 x$$

In the network of Figure 2, if

$$L_{11} = \frac{K_1 R}{\pi f r}$$

$$C_{12} = \frac{1}{4 \pi K_1 f r R}$$

and

$$x = \frac{f}{f r}$$

$f r$ being the resonant frequency of one impedance arm and the anti-resonant frequency of the other arm,

then

$$\theta = 2 \tan^{-1} \frac{K_1 x}{1 - x^2}$$

In Figure 3, if

$$L_{11} = \frac{K_2 R}{\pi f r_1}$$

$$C_{12} = \frac{p^2 - 1}{4 \pi K_2 f r_1 R}$$

and

$$L_{12} = \frac{K_2 R}{\pi f r_1 (p^2 - 1)}$$

then

$$\theta = 2 \tan^{-1} \frac{K_2 x (1 - x^2)}{1 - p^2 x^2}$$

where $f r_1$ and $f r_2$ are the resonant and anti-resonant frequencies of the impedance arms and

$$f r_1 = p f r_2$$

Figure 4 shows the phase angle θ of the network of Figure 2 plotted against $\log f$ for various values of K_1 . For all values of K_1 the phase angle at $f r$ is 180° and for values of K_1 greater than about 2, this curve is approximately linear over a considerable frequency range. Two such networks therefore with their resonance frequencies ($f r$) relatively displaced will give an approximately constant difference in phase. In general, the values of K_1 for the two networks should be the same or nearly the same. The optimum value of K_1 and the ratio of resonance frequencies for any given case depends upon the phase angle difference and frequency range required, and on the amount by which the phase angle difference may be permitted to depart from the desired value; however, K_1 will generally be found to be between 3 and 8 and the greater the permissible tolerance the greater is the frequency range which can be covered. By way of example Figure 5, shows a family of curves in which the phase difference between a pair of Figure 2 networks each having the same value of K_1 and designed by adjusting the ratio

$$\frac{f r A}{f r B}$$

of the resonance frequencies of the two networks to give a mean phase difference of 90° , is plotted against a logarithmic frequency scale. Thus for $K_1=3.4$ a frequency range of about $5\frac{1}{2}$ to 1 is obtained for $\theta=90 \pm 0.5^\circ$, while $K_1=5$ gives a range of about 75 to 1 for $\theta=90 \pm 7^\circ$. It is of interest that for a curve which varies equally above and below 90° the ratio

$$\frac{f r A}{f r B}$$

is approximately given by

$$\frac{f r A}{f r B} = 1.08 K_1$$

60 The use of networks containing a larger number

of elements or of a plurality of networks in tandem enables smaller deviations or larger frequency ranges to be obtained, and networks containing fewer elements may be used where it is only necessary to cover a small frequency range.

The network of Figure 3 for instance has a phase angle of 180° at its lower resonance frequency and 360° at its upper resonance frequency; these two points may be located at any desired points in the frequency range by the choice of values for the constants f_1 and p , while choice of the third parameter K_2 enables the value of θ to be fixed at one other point in the frequency range.

For example, a network similar to Figure 2 may be used in one branch of the circuit with a network similar to Figure 3 in the other branch. By choice of f_1 and p the resonance frequencies of the latter will be located at or near the frequencies at which the Figure 2 network gives phase angles of 90° and 270° respectively. The value of K_2 may then be chosen so that the Figure 3 network gives a phase angle of 270° at the resonance frequency (f_r) of the Figure 2 network. Under these conditions:

$$K_2 = p^{3/2} \text{ approximately}$$

The dotted curve of Figure 5 shows the phase difference between a Figure 2 network in which $K_1 = 3.4$ and a Figure 3 network in which $K_2 = 50.5p = 13.9$; the ratio

$$\frac{f_r}{f_r}$$

of the two networks is 3.73. With this arrangement $\theta = 90^\circ \pm 1.7$ over a frequency range of 43 to one.

With reference to the special case where a frequency difference of 90° is required it should be noted that the various networks give multiples of 180° at the frequencies in the following table:

	Network		
	180°	360°	540°
Figure 1.....	$\frac{f_r}{f_r}$	.....	.....
Figure 2.....	$\frac{f_r}{f_r}$	.....	.....
Figure 3.....	$\frac{f_1}{p} = f_r$	f_1	.....

The network of Figure 1 gives 90° phase angle at the frequency f_r/K_1 and is symmetrical with respect to $\log f$ about this point. In the network of Figure 2, the curve of θ against $\log f$ is symmetrical about the point where $f = f_r$. In the network of Figure 3 if $K_2 = p^{3/2}$ the curve of θ against $\log f$ is symmetrical about the point where $f = \sqrt{f_1 f_r}$ where $\theta = 270^\circ$. Thus a favourable arrangement consists of a pair of networks one of which has n elements per impedance arm and the other has $n+1$ elements per impedance arm. Each network will be designed so that its phase angle is substantially linear with respect to $\log f$ while the successive resonance points of the n element network will be located at the geometric means of the successive pairs of resonance points of the $n+1$ element network, i. e., if f_1, f_2, f_3 etc. are the resonance frequencies of the n element network and F_1, F_2, F_3 etc. those of the $n+1$ element network, then

$$f_1 = \sqrt{F_1 F_2}$$

$$f_2 = \sqrt{F_2 F_3} \text{ etc.}$$

The lattice network of Figure 2 can be replaced by a bridged T network of identical characteris-

tics shown in Figure 6. Where K_1 is greater than 1 the shunt inductance

$$L_{22} - \frac{1}{4} \cdot L_{11}$$

becomes negative and must be introduced by means of coupling between the inductances in the T arms; the network then takes the form shown in Figure 7, the coupling factor between the inductances L_0 being K' . As is well known the coupled inductances of Figure 7 may be represented by the T network of Figure 8, and if Figure 7 is equivalent to Figure 6, then:

$$L_0(1+K') = \frac{1}{2} \cdot L_{11} = \frac{RK_1}{2\pi f_r}$$

$$-K'L_0 = L_{22} - \frac{1}{4} \cdot L_{11} = \frac{R(1/K_1 - K_1)}{4\pi f_r}$$

$$\therefore \frac{K'}{1+K'} = \frac{K_1 - 1/K_1}{2K_1}$$

$$\therefore K' = \frac{K_1^2 - 1}{K_1^2 + 1}$$

The networks considered up to this point have all been of the constant resistance type and present their characteristic propagation constants, i. e., zero loss and an approximately logarithmic relation between phase angle and frequency, when terminated in their characteristic impedance; two such networks having their inputs connected in parallel, and each terminated in their characteristic impedance will give output voltages or currents of exactly equal amplitude and differing in phase by an approximately constant angle over the frequency range for which they are designed, the maximum angular deviation from the design value depending on the range to be covered. It has been found, however, that the performance can be improved by the inclusion of resistances in the networks and/or by modifying the terminating impedance.

The effect of such modifications is to reduce the angular deviation at the expense of a deviation from equality of amplitude.

A further advantage of the use of such resistance elements is that the unavoidable resistance of inductance coils may be absorbed in the said resistances thereby enabling coils of comparatively low 'Q' value to be employed.

For many applications and in particular for the single sideband modulator described later, deviations in angle and amplitude are both undesirable, but it has been found that the use of resistance elements in the networks makes it possible to reduce the effective maximum deviation (due to both phase and amplitude) over a given frequency range to a lower value than is obtainable with non-dissipative networks.

The aggregate effect of given deviations in angle and amplitude varies with different applications of the circuit, but in most cases a deviation in angle is approximately equivalent to an amplitude difference of 0.15 db. per degree, so long as the deviation is small. For example, in the single sideband modulator described later, the power ratio of the transmitted and suppressed sidebands is given by:

$$\frac{1 + a^2 + 2a \cos \theta}{1 + a^2 - 2a \cos \theta}$$

Where a is the amplitude ratio of the two input voltages and θ is the angular deviation from 90° of the phase difference between the input voltages; the amplitude ratio a which, with no angular deviation, gives the same suppression as an

angular deviation $\delta\theta$ with no amplitude deviation, is given by:

$$a = \sqrt{\frac{1-\sin \delta\theta}{1+\sin \delta\theta}}$$

From this formula, it can be shown that as $\delta\theta$ varies from 1-10°, a varies between .1512 and .1524 db. per degree.

Figure 9 shows by way of example a network similar to that of Figure 7 in which resistances r_1 are included in the T arms and resistances r_2 in the bridge arm. It is found that the attenuation frequency characteristic of this network is symmetrical about the resonant frequency of the network when $r_1=r_2$, and this condition is most generally useful. In particular cases it may be desirable to make r_1 and r_2 unequal in order to make the attenuation more constant over a part of the frequency range at the expense of less constancy over the remainder of the range. Figure 10 shows a pair of networks similar to Figure 9 having their inputs connected in parallel to a generator G and their outputs terminated in load impedances R_L , R_L^1 respectively. Currents or voltages in loads R_L , R_L^1 will be approximately equal in amplitude and will differ in phase by an approximately constant amount over a range of frequencies. The analytical determination of the optimum values of the various parameters to meet any given requirements is a matter of great complexity owing to the number of variables involved, and it has been found more convenient to use trial and error methods. By way of example the curves of Figure 11 show results which can be obtained with circuits designed for a phase difference of 90°; the useful frequency range expressed as the ratio of the highest and lowest frequencies is plotted against the maximum deviation which occurs in that range, deviation being expressed in db. The dotted curve 1 is for a pair of non-dissipative circuits of the type shown in Figure 2 or Figure 6. The full line curve 2 for a circuit of the type shown in Figure 10 in which:

$$r_1=r_2=r_1^1=r_2^1=r_0$$

$$R_L=R_L^1=R_0$$

and K_1 is the same for both networks.

In this case it appears that for a given deviation the increase in frequency range obtained by the addition of resistance varies from 10 to 20%.

The values which must be assigned to r_0 , R_0 and K_1 in order to give the optimum results for this type of circuit depend upon the frequency range to be covered. For frequency ranges from 5/1 to 50/1 it is found that r_0 varies from 0.27R to 0.5R, R_0 varies from 0.75R to 0.4R and K_1 varies from 3.5 to 5, where R is the characteristic impedance of the non-dissipative network.

An important application of the principle of the invention occurs in the design of frequency translating devices or modulators for single side-band working, especially where the carrier frequency is high compared with the input frequency, in which case the selection of one side-band by filters may be difficult or impracticable.

Figure 12 shows a known type of frequency translating device which is adapted to suppress one side-band; this circuit has not hitherto found much application for lack of convenient means to obtain over a sufficient frequency range a 90° phase shift with constant amplitude ratio between two circuits.

Modulators 1, 1¹ are supplied with the same carrier frequency from generator 2 but with a

phase difference of 90°. If this carrier frequency is constant, the required conditions can readily be attained by the use of an inductance and capacitance 3, 3¹ in the carrier supply circuit. If the carrier frequency is variable the inductance and capacitance should be replaced by a pair of networks in accordance with the invention. The modulating frequency from generator 4, which is frequently variable over a wide range, is applied to the translating device through phase networks 5, 5¹ whose output terminals are connected to the input terminals of modulators 1, 1¹ respectively, and whose input terminals are connected in parallel or over a hybrid coil or differential transformer. Networks 5, 5¹ which may be of the type shown in Figure 2 or Figure 3 are designed in accordance with the invention, so that currents or voltages in their output circuits differ in phase by 90° and have a constant amplitude ratio. The output circuits of modulators 1, 1¹ are connected in parallel or over a hybrid coil to line 6. Each modulator generates an upper and a lower sideband in its output circuit, but the phase relations are such that for one sideband the components from the two modulators are in phase and for the other sideband the components are 180° out of phase. Either sideband may be suppressed by suitable poling of the input, output and carrier circuits.

Figures 13 and 14 show frequency translating devices which are somewhat similar in principle to that of Figure 12, but which have other important advantages. In the circuit of Figure 13 the modulating frequency from generator 4 passes through phase networks 5, 5¹ designed for 90° phase difference, to the input circuits of modulator 1, 1¹. The carrier frequency from generator 2 is connected in the same phase to modulators 1, 1¹ and a second pair of phase networks 7, 7¹ similar to 5, 5¹ but designed to have a phase difference of 90° over the frequency range covered by the upper and lower sidebands are connected in the output circuits of modulators 1, 1¹.

The translating device of Figure 14 is similar to that of Figure 13 except that the input networks 5, 5¹ are omitted and the carriers supplied to modulators 1, 1¹ have a phase difference of 90°. Whereas the circuit of Figure 12 with one poling will suppress in its output the upper sideband of any input frequency, and with the other poling will suppress the lower sideband of any input frequency, the circuits of Figures 13 and 14 possess the property of discriminating between input frequencies, which lie respectively above and below the carrier frequency. The circuit of Figure 13 with one poling will suppress the upper sideband of input frequencies, which lie below the carrier frequency, and both sidebands of input frequencies which lie above the carrier frequency; with the other poling it will suppress the lower sideband of input frequencies which lie below the carrier frequency and neither sideband of input frequencies which lie above the carrier frequency.

The circuit of Figure 14 has properties inverse to those of Figure 13 and with one poling will suppress the upper sideband of frequencies which lie above the carrier frequency and both sidebands of frequencies which lie below the carrier frequency; with the other poling it will suppress the lower sideband of frequencies which lie above the carrier frequency, and neither sideband of frequencies which lie below the carrier frequency.

This feature is of considerable importance in frequency translating devices used in receiving circuits where it is necessary to eliminate which

is known as "second channel interference," and at the same time to eliminate in the output the upper sideband, due to the desired input frequency. This is illustrated by the circuit of Figure 15, in which 20 represents a frequency translating device of the type shown in Figure 12 or Figure 13 supplied with a carrier frequency p from generator 21 and an input frequency q (q less than p) from generator 22. The output of translating device 20 is arranged so that one sideband (say $p-q$) is suppressed and is connected to line 23. At the receiving end of the circuit line 23 is connected to the input of a frequency translating device 24 of the type of Figure 14, which is supplied with a carrier frequency p from generator 25, and whose output is connected to a load 26. The single sideband input of frequency $p+q$ will give rise to a lower sideband of frequency " q " in the load 26, the upper sideband $2p+q$ being suppressed. Furthermore, a frequency $p-q$ in line 23 e. g., from an adjacent channel, will not give rise to any output in load 26, since both sidebands q and $2p-q$ are suppressed. If it is required that the lower sideband $p-q$ be transmitted on line 23 instead of the upper sideband, then the frequency translating device 24 at the receiving end of the circuit should be of the type of Figure 13 instead of Figure 14. Figures 16 and 17 show alternative arrangements of the output circuits of frequency translating devices, in accordance with Figures 13 or 14. In Figure 16 the output terminals of networks $1, 1^1$ are connected to conjugate pairs of terminals on a hybrid coil 3. Across the other conjugate pairs of terminals are connected loads $4, 4^1$. The upper sideband will then appear in one load and the lower sideband in the other. The circuit of Figure 17 is only suitable for use where the ratio of the highest and lowest frequencies in the sideband range is small. The outputs of the modulators $1, 1^1$ are combined in a Maxwell bridge circuit comprising resistances $4, 4^1$ inductance 9 and capacitance 9^1 . At the mean sideband frequency the reactances of inductance 9 and capacitance 9^1 are made equal to the resistance of the loads $4, 4^1$ which are themselves equal. With this arrangement one sideband will appear in load 4 and the other in load 4^1 .

A further application of networks in accordance with the invention is to cathode ray oscilloscopes having a circular time base with a variable sweep frequency. A variable oscillator controlling the sweep frequency is connected to the vertical plates of an oscilloscope through a phase network, and to the horizontal plates through a second phase network, said networks being designed in accordance with the principles of the invention, so that the currents or voltages in their outputs differ in phase by 90° over the frequency range of the variable oscillator.

What is claimed is:

1. A transmission circuit capable of producing phase shifts of currents or voltages, which are substantially constant over a relatively wide range of frequencies, including a circuit having a plurality of branches and a network in each branch, each of said networks having an insertion phase angle bearing a substantially linear relation to the logarithm of the frequency, each of said networks depending solely upon its reactive characteristics in securing said phase shifts and any resistances present in said networks being always positive.

2. A circuit according to claim 1 in which the networks are chosen so that the ratios of the amplitudes of said currents or voltages in said branches are substantially constant over the said range of frequencies.

3. A circuit according to claim 1 in which the phase difference between two of said branches is substantially 90° .

4. A circuit according to claim 1 in which said networks are all-pass constant resistance networks.

5. A circuit according to claim 1 in which said networks are all-pass constant resistance networks in a lattice form and have two or more impedance elements in each impedance arm.

6. A circuit according to claim 1 in which said networks in lattice form have two impedance elements in each impedance arm and have substantially identical values of K_1 .

7. A circuit according to claim 1 in which said networks are of lattice form and at least one network has n impedance elements in each arm while at least one other network has $n+1$ impedance elements in each arm.

8. A circuit according to claim 1 in which said networks are of lattice form and at least one network has n impedance elements in each arm while at least one other network has $n+1$ impedance elements in each arm, and in which each resonance frequency of one of said n element networks is located approximately at the geometric mean of a pair of adjacent resonance frequencies of one of said $n+1$ element networks.

9. A circuit according to claim 1 in which said networks are all-pass constant resistance networks in which one or more resistance elements are inserted in one or more of the impedance arms.

10. A circuit according to claim 1 in which said networks are all-pass constant resistance networks whose load impedances are less than their characteristic impedances.

11. A circuit according to claim 1 in which each network comprises a bridged T network having a series arm comprising a capacitance and a resistance in series, two equal T arms each comprising an inductance and a resistance in series and a shunt arm comprising a negative inductance and a capacitance in series.

12. A circuit according to claim 1 in which each network comprises a bridged T network having a series arm comprising a capacitance and a resistance in series, two equal T arms each comprising an inductance and a resistance in series and a shunt arm comprising a negative inductance and a capacitance in series, and in which said resistance in said series arm is approximately twice said resistance in each of said T arms.

13. A circuit according to claim 1 in which each network comprises a bridged T network having a series arm comprising a capacitance and a resistance in series, two equal T arms each comprising an inductance and a resistance in series and a shunt arm comprising a negative inductance and a capacitance in series, said resistance in said series arm is approximately twice said resistance in each of said T arms, and in which each of said networks is terminated in a load resistance whose magnitude is less than the characteristic impedance of the non-dissipative part of said network.
